(57) **CLAIM**

The ornamental design for a pressure gauge top having an ornamental logo thereon, as shown and described.

DESCRIPTION

FIG. 1 is a front perspective view of a preferred embodiment of the pressure gauge according to the present design, illustrating a flat top surface;

FIG. 2 is a top plan view of the pressure gauge of FIG. 1; FIG. 3 is a front perspective view of another preferred embodiment of the pressure gauge according to the present design, illustrating a domed top surface; and,

FIG. 4 is a top plan view of the pressure gauge of FIG. 3. The broken line showing the body of the pressure gauge is for illustrative purposes only and forms no part of the claimed design.

1 Claim, 2 Drawing Sheets

FIG. 2

FIG. 1

FIG. 4

FIG. 3
